ATTORNEY.

UNITED STATES PATENT OFFICE.

JOSEPH H. CROSBY, OF JACKSONVILLE, FLORIDA, ASSIGNOR TO GREEN-LEAF AND CROSBY COMPANY, A CORPORATION OF FLORIDA.

DESIGN FOR A BROOCH OR SIMILAR ARTICLE.

No. 37,790.

Specification for Design.

Patented Jan. 23, 1906.

Application filed December 12, 1905. Serial No. 291,491. Term of patent 7 years.

To all whom it may concern:

Be it known that I, JOSEPH H. CROSBY, a citizen of the United States, residing at Jacksonville, in the county of Duval and State of Florida, have invented a new, original, and ornamental Design for a Brooch or Similar Article, of which the following is a specification, reference being had therein to the accompanying drawing.

The figure is a front view of a brooch embodying my new design.

I claim—

The ornamental design for a brooch or similar article as shown.

JOSEPH H. CROSBY.
